DESIGN FOR A CIGARETTE LIGHTER

Kurt Adler, Scranton, Pa., and Harry H.
Rosenthal, New York, N. Y.

Application July 22, 1947, Serial No. 140,456-

Term of patent 7 years

(Cl. D48—27)

To all whom it may concern:

Be it known that we, Kurt Adler, a citizen of the United States of America, and residing in the city of Scranton, county of Lackawanna, and State of Pennsylvania and Harry H. Rosenthal, a citizen of the United States of America, and residing in the Borough of Bronx, city of New York, county of Bronx, and State of New York, have invented a new, original, and ornamental Design for a Cigarette Lighter, of which the following is a specification, reference being had to the accompanying drawing, forming part thereof:

Figure 1 is an exploded elevational view of a cigarette lighter, showing our new design; Figure 2 is an end elevational view of the cigarette lighter of Figure 1 with the cover in place; Figure 3 is a plan view; and Figure 4 is a view in perspective.

We claim:

The ornamental design for a cigarette lighter, as shown.

KURT ADLER.
HARRY H. ROSENTHAL.
